UNITED STATES PATENT OFFICE

HARRY N. GITT, 2D, OF HANOVER, PENNSYLVANIA

HAND BALL GLOVE

Application filed July 8, 1932. Serial No. 621,337.

The objects of this invention are to provide a glove suited to the playing of hand ball or the like, which will be sufficiently open for ventilation purposes, which will closely but comfortably fit the hand and which will be made to instantly and automatically conform to the hand in the act of securing it in position.

These and other desirable objects as will later appear, are accomplished by the novel features of construction, combination and relation of parts hereinafter described in the specification and broadly covered in the claims.

15 The drawing accompanying and forming part of the specification illustrates by way of example two of the many possible embodiments of the invention, it being understood that the structure may be modified as regards 20 this disclosure without departure from the true spirit and broad scope of the invention.

Fig. 1 is a perspective view showing the structure and illustrating the mode of simultaneously fitting and securing the glove in 25 place on the hand.

Fig. 2 is an enlarged broken sectional detail as on line 2—2 of Fig. 1.

Fig. 3 is a back view of another form of 30 the glove, fully open, ready to slip easily over the hand.

Fig. 4 is a broken sectional detail as on line 4—4 of Fig. 3.

One characteristic of the glove is that it 35 is fully open in the back as indicated at 5, both for ventilation and for free fitting purposes. This opening is shown as including the greater portion of the back of the glove and as extending well up to or beyond the knuckle portion of the glove.

40 Surrounding the back opening is a tubular guide 6 containing a cord 7, which slides through said guide in the nature of a "draw string" to close the opening to the extent required to fit the glove to the individual hand.

45 One end of the draw cord is shown in Fig. 1, as extending from one end of the guide tube across the back opening and through a loop 8, secured to the wrist portion of the glove at the opposite side of the opening and the two ends of the cord are shown as

then drawn together and secured as by a suitable fastener 9, to the opposite wrist portion at the base of the thumb. The fastener 9 may be of the spring disc type on which the cords are held in any adjusted relation by simply twisting them about the shank of the fastener beneath the spring disc portion of the same, but while such a fastener is desirable, the invention is not limited to such particular form of fastener.

55 The guide tube may be formed or applied in various ways. Thus in Fig. 1, it is shown as a strip caught along one edge, at the outside of the glove beneath the stitching which holds the binding 10 about the edge of the opening, said strip being reversed over the binding and having its inner edge secured inside the glove by a row of stitching 11, which latter may be the same which secures the inner edge of the binding as plainly indicated in Fig. 2.

60 The form of the invention illustrated in Fig. 3 is similar to that just described in that the draw cord is run through a guide tube about the open back of the glove and is then brought across the wrist to simultaneously adjust and secure the glove in place, but the 65 possibility of puckering is avoided by notching the back of the glove, about the opening 70 as indicated at 12 and the loop is formed by turning the material back upon itself as in Fig. 4 and securing it by stitching 13. Also in this instance, an eyelet 14 is used in place of the loop 8 at the side of the wrist opening 75 opposite the fastener.

80 Usually after passage of the cord through the guide loop and the passage of one end of the cord through the loop 8 or eyelet 14, the two ends of the cord will be brought together and knotted as indicated at 15. This 85 knot serves as a finger hold for pulling on the cord to draw the opening closed as much as desired over the back of the hand and for closing the wrist portions and catching the 90 cord in the holder or clasp 9. In such adjusting and securing operations, the cord can 95 slide freely through the guide loop or tube and hence equalize the pull in fitting the glove as tight as desired to the hand and 100 about the wrist.

The invention it will be seen enables the glove to be instantly fitted to the desired extent in the same simple action of securing the glove in place. Full ventilation is afforded and even though the glove may be fitted quite tight, freedom for necessary hand movements are permitted by the slidability of the cord through the guide surrounding the back opening.

5 10 The glove may be made of various materials, such as leather, cloth, or partly of both leather and cloth. The Figure 3 construction is particularly suited to a cloth back glove, which can incorporate the advantages 15 of the invention quite inexpensively. By accurately fitting the glove to the hand and wrist, gaping, puckering and bulging are avoided and the palm of the glove in particular, can be kept free of wrinkles. In addition to the many advantages pointed out, 20 the glove may be more quickly applied to or freed from the hand, since there is only the one fastening which can be instantly tightened and secured, or be wholly released.

25 5. What is claimed is:

1. A glove for hand ball or the like, said glove having an open back with guide tubing about the edges of such opening and a draw cord extending through said guide tubing and secured across the separated wrist portions at the back of the glove.

2. A glove for hand ball or the like, said glove having an open back with separated wrist portions and with guide tubing extending 35 about the back opening above the separated wrist portions, a draw cord extending through said guide tubing and means for securing the end portions of said draw cord in crossed relation across the separated wrist 40 portions of the glove to thereby conjointly contract the glove over the back of the hand and secure the glove about the wrist of the hand.

3. An open back glove having a guide 45 about the back opening, a guide on the wrist portion of the glove at one side of the back opening, a fastener on the wrist portion of the glove at the opposite side of the back opening and a cord slidingly extending 50 through the guide about the back opening and having one end of the same extending through the guide on the wrist portion and said fastening being positioned and constructed to adjustably secure both end portions of the cord when pulled to contract the 55 back opening and draw the wrist portions of the glove together.

4. A glove having an opening in the back of the same with guiding means about the 60 edge of said opening, a guide on the wrist portion at one side of said back opening, a cord holder on the wrist portion of the glove at the opposite side of said opening, a cord 65 extending slidingly through the guiding means about the back opening, the end of the

the cord at the side opposite the guide on the wrist portion being extended across the back opening and through said guide, across to the cord fastener on the opposite wrist portion and the other end of the cord extending across the back of the opening in crossed relation to the first mentioned end portion, directly to the cord fastener, whereby simple pull of the two end portions of the cord, will contract the back portion and bring the 75 wrist portions together.

5. A glove having an opening in the back of the same with guiding means about the edge of said opening, a guide on the wrist portion at one side of said back opening, a cord holder on the wrist portion of the glove at the opposite side of said opening, a cord extending slidingly through the guiding means about the back opening, the end of the cord at the side opposite the guide on the wrist portion being extended across the back opening and through said guide, across to the cord fastener on the opposite wrist portion and the other end of the cord extending across the back of the opening in crossed relation to the first mentioned end portion, directly to the cord fastener, whereby simple pull of the two end portions of the cord, will contract the back portion and bring the 95 wrist portions together, the guiding means being in the form of flexible tubing secured continuously about the edge of the back opening.

6. A glove having an opening in the back of the same with guiding means about the 100 edge of said opening, a guide on the wrist portion at one side of said back opening, a cord holder on the wrist portion of the glove at the opposite side of said opening, a cord extending slidingly through the guiding means about the back opening, the end of the cord at the side opposite the guide on the wrist portion being extended across the back opening and through said guide across to the cord fastener on the opposite wrist portion and the other end of the cord extending across the back of the opening in crossed relation to the first mentioned end portion, directly to the cord fastener, whereby simple pull of the two end portions of the cord, will contract the back portion and bring the 115 wrist portions together, said guiding means including a binding secured about the back opening and a flexible strip caught at the outside beneath said binding and doubled over and secured to the inside of the glove.

7. A glove having an opening in the back of the same with guiding means about the edge of said opening, a guide on the wrist portion at one side of said back opening, a cord holder on the wrist portion of the glove at the opposite side of said opening, a cord extending slidingly through the guiding means about the back opening, the end of the cord 130

at the side opposite the guide on the wrist portion being extended across the back opening and through said guide across to the cord fastener on the opposite wrist portion and the 5 other end of the cord extending across the back of the opening in crossed relation to the first mentioned end portion directly to the cord fastener, whereby simple pull of the two end portions of the cord, will contract the 10 back portion and bring the wrist portions together, said guiding means including tubing secured about the edge of the back opening and notched through into the back of the glove to avoid puckering.

15 In testimony whereof I affix my signature.

HARRY N. GITT, 2d.
